 Bendix Aviation Corporation, Teterboro, N. J.,
 a corporation of Delaware

Original application April 1, 1948, Serial No.
 18,433. Divided and this application October
 13, 1949, Serial No. 121,115

4 Claims. (Cl. 175—335)

1

This application is a division of application Serial No. 18,433, filed April 1, 1948 now U. S. Patent 2,533,038 and relates to improvements in a carbon pile regulator of the type disclosed in the copending U. S. application Serial No. 684,379, filed July 17, 1946 by William G. Neild, now U. S. Patent 2,506,234.

An object of the invention is to provide an improved housing for a regulator; including a novel arrangement for shielding a voltage calibrating device, while permitting the ready adjustment thereof.

Another object of the invention is to provide a novel and compact arrangement for a carbon pile regulator in which all adjustable parts are enclosed to prevent tampering by unauthorized personnel.

The above and other objects and features of the invention will appear more fully hereinafter from a consideration of the following description taken in connection with the accompanying drawings wherein two embodiments of the invention are illustrated by way of example.

In the drawings:

Figure 1 is a longitudinal sectional view of the regulator.

Figure 2 is a fragmentary view of the armature spring and mounting arrangement.

Figure 3 is a fragmentary view of a modified form of the spring arrangement.

Figure 4 is an end view of the regulator housing showing the novel voltage adjustment and voltmeter test jacks provided therein.

Referring to the drawing of Figure 1, a carbon pile is illustrated at 10 and comprises a number of hollow discs of carbon which are stacked within a tube 11. The tube 11 is preferably formed of a suitable ceramic electrical insulating material to carry away the heat developed by the carbon pile 10. The carbon pile 10 is of a suitable size and length to develop the desired regulating characteristics. The tube 11 is received within a metal shell 12 and, in order to facilitate the dissipation of the heat, the shell is preferably provided with fins 13 over its length so as to more readily dissipate the heat away from the pile and increase the capacity of the pile.

Contact elements 14 and 15 are adjustably mounted within the tube 11 at the opposite ends of the carbon pile 10. The contact element 14 fits loosely in the tube 11 and has mounted thereon a button 16 which bears upon an engaging element 17 of an armature 18 for regulation of the carbon pile 10, as will be explained hereinafter.

2

Affixed at one end to the contact element 15 is a tubular member 20 formed of a material such as copper having a relatively high temperature coefficient of expansion. The tubular member 20 projects interiorly within the hollow carbon discs 10 and is secured to its other end by a pin 22 one end of a rod 24 formed of a material having a low temperature coefficient of expansion such as Invar. The opposite end of the rod 24 is connected by a pin 26 to a screw 28 adjustably mounted in a plate 30.

The plate 30 is fastened to the shell 12 by bolts 32 which are suitably insulated by member 34 from the plate 30. The plate 30 is also insulated from the shell 12 by a suitable insulating strip 36.

Through the latter arrangement, it will be seen that upon an increase in temperature tending to cause the pile 10 to lengthen, the tube 20 having a high temperature coefficient of expansion will also tend to lengthen relative to the rod 24 causing the contact element 15 to move toward the right so as to compensate for the lengthening of the pile due to such rise in temperature.

A decrease in temperature will have the opposite effect on the tube 20 so that the tube will tend to move the contact element 15 toward the left to compensate for the temperature effect on the carbon pile 10.

It will be seen then that with the tube 20 projecting interiorly within the hollow carbon discs 10, the same will be directly responsive to the temperature of the carbon pile 10 so as to more accurately compensate for variations in the length of the pile due to change in temperature.

At the opposite end of the carbon pile 10, the contact element 14 is regulated by action of the armature 18 so as to vary the compressive force applied on the carbon pile 10 and accordingly the resistance thereof. The armature 18 and spring assembly therefore may be of a type disclosed and claimed in the copending application Serial No. 684,379, filed July 17, 1946 by William G. Neild, now U. S. Patent 2,506,234.

As shown in Figure 1 the armature 18 includes a flexible metal hinge 38 which has one end riveted to the armature 18 and the other end fastened by bolt 40 and bar 42 to one end of a U-shaped supporting member 44 having legs which extend at opposite sides of an electromagnet 46. The electromagnet 46 is fastened by bolts 48 to a supporting plate 49. The bolts 48 also serve to secure the U-shaped member 44 to the plate 49. Screw threadedly engaged in the

plate 49 is an adjustable electromagnetic core 50, which projects through the electromagnet 46 into operating spaced relation to the armature 18. The plate 49 is fastened to the shell 12 by rods 52, as shown in Figure 1.

While one end of the armature 18 is flexibly connected by the hinge member 38, the opposite end of the armature 18 is operatively connected to a spring mechanism indicated generally by the numeral 54 and shown in Figures 1 and 2.

The aforesaid mechanism includes a ball bearing 56 which rides at one side in a seat 58 carried by the armature 18, while the opposite side of the ball bearing rides in a seat 60 formed in an adjustable member 62. The member 62 has projecting therefrom a stem portion 64 having screw threads 66 which engage in corresponding internal threads formed in a member 68. A lock nut 70 serves to fasten the screw 62 in adjusted position relative to the member 68. The member 68, as best shown in Figure 2, extends at a ninety degree angle to the plate 49. One side of the member 68 is fastened by bolts 72 to one end of a curved metal spring blade 75. The other end of the spring blade 75 is fastened to the supporting plate 49 by bolts 76. At the opposite side of the member 68, there is fastened by nut 73 of bolt 72 one end of a similar curved metal spring blade 75. The opposite end of the latter curved metal spring blade 75 is similarly fastened to the supporting member 49 by like bolts indicated by the numeral 76. In operation it will be seen that upon a force being applied at the armature 18 by the electromagnet 46, the spring blades 75 will tend to wrap or roll on the surface of the vertical member 68 and the horizontal member 49 as the armature 18 moves under the force of electromagnet 46. Such action will decrease the radius of the spring 75 and greatly increase its resistance to force, so as to provide a force deflection curve which very closely resembles an inverse square curve and effect a rolling non-slipping action with a minimum friction.

The latter force deflection curve will closely approximate that of the electromagnet 46 which will apply a force to the armature 18 which continuously increases in excess of a linear relation as the armature 18 approaches the electromagnet 46 and which force will vary approximately inversely as the square of the distance between the armature and magnet. Thus, the opposing armature spring 75 is arranged to compensate for the varying force applied by the electromagnet 46 to the armature 18. Basic correspondence between the force of the spring 75 and the electromagnet 46 may be conveniently affected by adjusting the member 62 of the spring mechanism 54 and the core 50 of the magnet 46 so that the force of the one matches that of the other.

A modified form of the spring arrangement is shown in Figure 3 in which corresponding numerals indicate like parts to those described in Figure 2.

In the arrangement of Figure 3, the member 68 is split at 77 to provide leg portions 78 and 79 which have an inherent spring tension tending to bias the legs 78 and 79 inward. A wedge-like screw 80 is screw threadedly engaged in the split portion 77 of the member 68 for adjusting the leg portions 78 and 79 relative to the spring blades 75. The screw 80 has a cleft portion 82 readily accessible through an opening 84 in the plate 49 so that the screw 80 may be readily manually

adjusted by means of a screw driver or other suitable tool.

The adjustment of the leg portions 78 and 79 relative to the spring blades 75 permits the force characteristic of the spring blades 75 to be varied so that the force deflection curve of the springs 75 may be matched more closely with the force of the electromagnet 46.

A further feature of the invention resides in the provision of a leaf spring 85 fastened at opposite ends to the shell 12, as shown in Figure 2. Connected to the leaf spring 85 intermediate its opposite ends is the button 16. The leaf spring 85 biases the floating contact element 14 which is loosely positioned in tube 11 towards the armature 18. The armature 18 is spring hinged at 38 and biased by the spring mechanism 54 in a clockwise direction. The leaf spring 85 serves to keep the pile 10 together in the event the whole armature end should be removed and also centers the button 16 in relation to the member 17 of the armature 18 without hand-fitting or complicated linkage.

A cover cap 86, shown in Figure 1, fits lightly about one end of the shell 12 and surrounds the armature spring assembly so as to protect the same from dust and possible injury. The cover cap 86 is fastened in position by a suitable screw 87.

At the opposite end of the shell 12 there is provided a bracket 90, as shown in Figure 1, fastened to the shell 12 by a nut 92 screw threadedly engaged on rod 52. Mounted in the bracket 90 are jacks or electrical connectors 93 and an adjustable resistor 94 having a rotatable arm not shown which may be adjustably positioned on a resistor 98 by adjustment of a rotatable slotted head member 100. The variable resistor 94 has the variable resistance element 98 connected in series with the electromagnetic coil 46 so as to set the value of the electrical condition or voltage for which the coil 46 is to regulate. The jacks 93 are suitably connected across the regulated condition or voltage so that a voltmeter or other measuring instrument may be connected into the circuit through the jacks for testing purposes. A cover cap 102 is fastened to the bracket 90 by bolt 104. The cover cap 102 fits tightly about the latter end of the shell 12 and protects the calibrating resistor 94 from dust and possible damage. Suitable openings are formed in the end of the cover cap 102 so as to permit the ends of the jacks 93 and the slotted head 100 of the adjustable resistor 94 to project therethrough.

This arrangement, which permits only head 100 to be exposed, is safe both electrically and mechanically. In former units where the resistor 94 was externally located there was provided fire hazards from "hot" wiring.

The entire regulator assembly may be conveniently mounted on a base plate 105 which in turn is supported by suitable shock mounts indicated generally by the numeral 110, as shown in Figure 4.

Suitable electrical conductors, not shown, lead from one end of the carbon pile 10, while another suitable electrical conductor leads from the other end of the carbon pile 10. These electrical conductors lead in turn to an insulated terminal board, not shown, which may be mounted in the base plate 105 so that the carbon pile may be conveniently connected into the regulating circuit as is well known in the art. Electrical conductors also lead from the terminal board to the electromagnet 46 through the

calibrating resistor 94 so that the same may be responsive to the regulated condition or voltage.

In the operation of the spring mechanism 54, in the arrangement shown in Figures 1 and 2, it will be seen that as the armature 18 is drawn towards the electromagnetic core 50, the spring plates 75 will roll or wrap along the member 68 and in toward the center on the horizontal member 49 and thereby decrease the radius of the curve 75 and increase the resistance of the spring 75 to the magnet force so as to effect basic correspondence with the nonlinear force characteristic of the electromagnet 46.

Through the arrangement of the ball bearing 56 the element 62 may be conveniently rotated so as to vary the tension of the springs 75 and thereby match the deflection curve of the spring 75 with that of the electromagnet 46. Through the adjustment screw 82 of Figure 3 the characteristic of the spring 75 may be varied so as to more accurately balance or match the electromagnet 46.

It will be further seen that upon changes in temperature tending to vary the length of the pile 10, the adjustment of the contact element 15 through the coaction of the tube 20 and rod 24 will readily compensate for such changes in temperature.

Although only one embodiment of the invention has been illustrated and described, various changes in the form and relative arrangements of the parts may be made to suit requirements.

What is claimed is:

1. In an electrical regulator of the type including a variable resistance means, a housing for said means, an electromagnet, an armature movably mounted in relation to said electromagnet, means operatively connecting the armature to the variable electrical resistance means; the improvement comprising a bracket carried by said housing, a calibrating resistor for varying the setting of said electromagnet, said calibrating resistor supported by said bracket, an adjustable member for varying said calibrating resistor, a cover cap fastened to said bracket and enclosing said calibrating resistor and bracket so as to shield said adjustable member from accidental displacement, said cover cap fitting tightly about one end of the housing and having an opening formed therein, and said adjustable member having a cleft portion accessible for manual adjustment through said opening in the cover cap.

2. The combination defined by claim 1 including a pair of connector jacks carried by said bracket and shielded by said cover cap, said cover cap having other openings formed therein for access to said jacks, and said jacks connected to the input to said electromagnet so that adjustment of the setting of said electromagnet by said calibrating resistor may be readily tested through said jacks without the removal of said cover cap.

3. In an electrical regulator of the type including a variable resistance means, a housing for said means, an electromagnet, an armature movably mounted in relation to said electromagnet, means operatively connecting the armature to the variable electrical resistance means, the improvement comprising a bracket, means for securing said bracket to said housing, a variable resistor for selectively adjusting said electromagnet, means including said bracket for mounting said resistor, an adjustable member for varying said resistor, a substantially cup-shaped cover adapted to coact with said housing to enclose said bracket and said resistor, said cover having an opening formed therein, said adjustable member having a slotted portion positioned for accessibility for manual adjustment through said opening in said cover.

4. The combination defined by claim 3 including a plurality of test jacks supported by said bracket and enclosed by said cover, said cover having other openings formed therein, said last openings and said jacks being so positioned relative to each other to provide access to said jacks, said jacks being connected to said electromagnet so that electrical condition of said electromagnet may be readily tested through said jacks without the removal of said cover.
